CATHETER FOR BRONCHOSPIROMETRY

Paul W. Gebauer, Cleveland, Ohio, assignor to
American Anode Inc., Akron, Ohio, a corpora-
tion of Delaware

Application November 26, 1938, Serial No. 242,490

7 Claims. (Cl. 128—349)

This invention relates to surgical accessories and particularly to a special catheter for use in broncho-spirometry and for other purposes.

The invention aims to provide a compact 5 multi-tubed structure adapted to be readily inserted in the respiratory passages of a patient, with minimum difficulty and discomfort, for conducting gaseous materials between each of the lungs, individually, and respective, separate 10 spirometers, and further aims to provide simple but assuredly effective means for occluding the respiratory passages at appropriate points for sealing the lungs from each other and from the outside atmosphere, whereby the functional capacity of each lung may be determined separately and simultaneously.

The invention may be readily understood by referring to the accompanying drawing, of which—

20 Fig. 1 is an elevation showing a catheter embodying the principles of the present inventions in a preferred form;

Fig. 2 is a vertical section taken on line 2—2 of Fig. 1;

25 Fig. 3 is a vertical section taken on line 3—3 of Fig. 1;

Fig. 4 is a vertical section taken on line 4—4 of Fig. 1;

30 Fig. 5 is a vertical section taken on line 5—5 of Fig. 1;

Fig. 6 is a horizontal section taken on line 6—6 of Fig. 5;

Fig. 7 is a fragmentary elevation of a catheter generally similar to the catheter of Figs. 1—6, 35 but embody a curved distal end; and

Fig. 8 is a diagrammatic view illustrating the manner in which the present catheter is employed in carrying out differential broncho-spirometry upon a patient.

40 The invention contemplates a catheter adapted to be inserted in the respiratory passages of a patient and having two longitudinal passageways or conduits with separate openings adapted to communicate respectively with the two lungs, 45 and also includes two separate sealing means so positioned on the catheter as to seal the lungs from each other and from the outside atmosphere and force breathing through the respective conduits of the catheter.

50 Such a catheter as illustrated in the drawing comprises a relatively long tubular structure 10 adapted to extend from a point outside the mouth of a patient, through the mouth and trachea, to a point at least within the main 55 bronchus of one lung. One opening 11 is pro-

vided in the wall of the tubular structure 10 at a point adjacent the distal end which will be positioned within the bronchus of one lung, as by leaving the entire end of the catheter open as illustrated. A second opening 12 is provided in the wall of the tubular structure 10 at a point proximal to the first opening and in a position adapted to communicate with the other lung. The lumen of the tubular portion 10 is divided into two separate fluid conduits 13 and 14 by 10 means of a septum 15 extending from the proximal end of the tubular portion 10 to a point 16 between the two openings 11 and 12 at which point the septum 15 curves toward and is attached to the wall of the tube to form a closed 15 end for one of the conduits 13. The two fluid conduits 13 and 14 diverge at the proximal end of the tubular portion and terminate in separate tubular extensions 17 and 18, respectively, adapted to be connected to any appropriate fluid 20 conductors such as conductors leading to separate spirometers.

For sealing the respiratory passages about the inserted catheter, two inflatable collars 19 and 20, are provided encircling the tubular structure 25 10 at longitudinally spaced-apart positions, one collar 19 being located adjacent the distal end of the catheter between the two openings 11 and 12, and the second inflatable collar 20 being located proximal to the opening 12 so that the 30 opening 12 is located between the two inflatable collars while the opening 11 is distal to both collars.

For inflating the collars 19 and 20, a relatively small inflating duct 21 is provided extending 35 longitudinally through the walls of the tubular structure 10 from a point adjacent the proximal end to both inflatable collars 19 and 20, communicating openings 22, 23 being provided 40 through the walls of the tubular structure 10 underneath the inflatable collars 19, 20, respectively, for conducting inflating fluid thereto. At the proximal end of the catheter, the inflating duct 21 diverges from the tubular structure and terminates in a tubular extension 24 adapted to 45 be connected to any suitable apparatus for injecting fluid under pressure.

For facilitating entrance of the catheter into the main bronchus of a lung, the distal end of the tubular structure 10 desirably is preformed 50 with a permanently-set arcuate configuration as indicated at 25 in the modified form of the catheter illustrated in Fig. 7, the catheter being otherwise similar in construction to the catheter illustrated in Figs. 1—6. The most satisfactory 55

arcuate configuration appears to be obtained by gently curving the distal end of the catheter from a point distal to the opening 11 so that the distal tip of the catheter is directed at an angle 5 of approximately 60° to the axis of the rest of the tubular portion 10, although no particular curvature is essential.

In order to facilitate ready passage of the catheter through the tortuous channels of the 10 mouth, trachea and bronchus with minimum difficulty and discomfort, the entire catheter preferably is made essentially of a flexible soft rubber or analogous composition, although it is to be understood that other materials, such as 15 conventional fabric, metal or wire reinforcements, may be associated with the essentially rubber structure so long as the essential flexibility of the rubber is not destroyed. The catheter desirably has a one-piece, unitary structure 20 to avoid all possibility of parts becoming disconnected or separated while in use, although satisfactory catheters obviously may be fabricated by assembling separate pre-formed parts of rubber or other flexible material and cementing or 25 otherwise mounting the parts in proper relation. Procedures for manufacturing such structures are well known in the rubber industry and form no part of the present invention.

To use the present catheter for carrying out 30 differential broncho-spirometry, the catheter is passed through the respiratory passages of a patient, as indicated in Fig. 8, until the distal end of the catheter including the inflatable collar 19 is positioned with the main bronchus 31 of one lung, usually the left lung. The second inflatable collar 20 will then be positioned within the trachea 32. Using any suitable device, air or other inflating fluid is injected 35 through the tube 24 and duct 21 until the collars 19 and 20 have been inflated sufficiently to seal the bronchus and trachea, respectively, about the catheter, the inflated collars conforming readily to irregularities in the passageway 40 walls to effect an assuredly effective seal which is maintained as by clamping the tube 24. When the collars have been inflated, the patient, of course, breathes through the catheter, the left lung receiving and discharging gases through 45 the opening 11 and the communicating tubes 14 and 18, while the right lung receives and discharges gases through the opening 12 and the communicating tubes 13 and 17. The tubular extensions 17 and 18 are connected to separate 50 spirometers which measure characteristic factors concerning the intake and discharge gases and afford a basis for calculating the functional capacity or efficiency of each lung separately and simultaneously. The spirometer itself of course 55 is a known apparatus.

The present invention is especially useful in examinations conducted as a preliminary to treating a patient suffering from pulmonary tuberculosis when it is vitally important to know accurately 60 the relative functional efficiencies of the two lungs in order that the character and extent of treatment which may safely be undertaken on either lung can be reliably judged. The catheter obviously is capable of other uses however.

70 Numerous modifications and variations in details of structure and materials embodied in the catheter for broncho spirometry as hereinabove described may be made without departing from the spirit and scope of the invention as defined 75 by the appended claims.

I claim:

1. A surgical accessory comprising a tubular structure of elongated configuration having at least three longitudinal conduits each separate from the others, a plurality of inflatable collars 5 encircling the tubular structure at longitudinally spaced-apart positions, each of said inflatable collars communicating with at least one of said conduits for receiving inflating fluid therefrom, the walls of said tubular structure having a plurality 10 of openings therein at positions removed from the positions of the inflatable collars, each of said openings communicating with one of said conduits and at least two of said conduits communicating with different openings, the proximal ends 15 of said conduits being adapted to be connected with appropriate fluid conductors, said surgical accessory being flexible and comprising a rubbery composition as its principal constituent.

2. A surgical accessory comprising a tubular 20 structure adapted to be inserted in a body passage, an inflatable collar encircling the tubular structure at a position adjacent the distal end thereof, a second inflatable collar encircling the tubular structure at a position proximal to the 25 first collar, means for inflating the collars including an inflating duct extending longitudinally through the said structure and communicating with at least one of the inflatable collars for conducting inflating fluid thereto, the walls of said 30 tubular structure having one opening distal to both inflatable collars and a second opening proximal to at least one of the collars, and a septum dividing the lumen of said tubular structure into two separate conduits communicating 35 respectively with the aforesaid two openings, said conduits and said inflating duct diverging at the proximal end of the tubular structure and terminating in separate tubular extensions adapted to be connected to appropriate fluid conduits, said 40 accessory having an essentially unitary structure embodying rubber as the principal ingredient and being flexible throughout.

3. A catheter for differential broncho-spirometry adapted to be inserted in the respiratory 45 passages of a patient for conducting gaseous materials to and from the lungs separately and simultaneously, said catheter comprising a tubular structure adapted to extend through the trachea to a point within the bronchus of a lung, means 50 for sealing the said bronchus about the tubular structure, separate means for sealing the trachea about the tubular structure, the walls of said tubular structure having one opening distal to both sealing means and a second opening between the two sealing means, said tubular structure having two separate longitudinal conduits 55 communicating respectively with the aforesaid two openings, said catheter having a unitary 60 structure and being flexible throughout.

4. A catheter for differential broncho-spirometry adapted to be inserted in the respiratory 65 passages of a patient for conducting gaseous materials to and from the lungs separately and simultaneously, said catheter comprising a tubular structure adapted to extend through the trachea to a point within the bronchus of one lung, an inflatable portion adapted to seal the said bronchus, a second inflatable portion adapted to seal the trachea, means for inflating the two inflatable portions, the walls of said tubular structure having one opening distal to both inflatable 70 portions and a second opening between the two inflatable portions, said tubular structure having 75

- two separate longitudinal conduits communicating respectively with the aforesaid two openings, the proximal ends of said conduits being adapted to be connected with appropriate fluid conductors, said catheter being flexible throughout. 5
5. A catheter for differential broncho-spirometry adapted to be inserted in the respiratory passages of a patient for conducting gaseous materials to and from the lungs separately and simultaneously, said catheter comprising a tubular structure adapted to extend at least from the mouth of a patient to a point within the main bronchus of one lung, an inflatable collar encircling the tubular structure at a position adjacent 10 the distal end thereof and adapted to be positioned within the said bronchus, a second inflatable collar encircling the tubular structure at a position proximal to the first collar and which will be positioned within the trachea when the 15 first collar is positioned within the bronchus of one lung, said collars being adapted to seal the respective respiratory passages when inflated, inflating duct means for conducting inflating fluid to said collars, the walls of said tubular structure 20 having one opening distal to both collars and a second opening between the two collars, a septum dividing the lumen of said tubular structure into two separate longitudinal conduits communicating respectively with the aforesaid two openings, 25 the proximal ends of said conduits and of said inflating duct means being adapted to be connected to appropriate fluid conductors, said catheter embodying rubber as the principal constituent and being flexible throughout. 30
35. 6. A catheter for differential broncho-spirometry adapted to be inserted in the respiratory passages of a patient for conducting gaseous materials to and from the lungs separately and simultaneously, said catheter comprising a tubular structure adapted to extend at least from the mouth of a patient to a point within the main bronchus of one lung, an inflatable collar encircling the tubular structure at a position adjacent 40 the distal end thereof and adapted to be positioned within the said bronchus, a second inflatable collar encircling the tubular structure at a position proximal to the first collar and which will be positioned within the trachea when the first collar is positioned within the bronchus of 45 one lung, said collars being adapted when inflated to seal the respective respiratory passages, a single inflating duct extending longitudinally through a wall of said structure and communicat- 50
- ing with both of said collars for conducting inflating fluid to the collars, the walls of said tubular structure having one opening distal to both collars and a second opening between the two collars, a septum dividing the lumen of said tubular structure into two separate longitudinal conduits 5 10 communicating respectively with the aforesaid openings, said conduits and said inflating duct diverging at the proximal end of the catheter and terminating in three separate tubular extensions adapted to be connected with appropriate fluid conductors, said catheter having an essentially integral unitary structure embodying rubber as the principal constituent and being flexible throughout. 15
7. A catheter for differential broncho-spirometry adapted to be inserted in the respiratory passages of a patient for conducting gaseous materials to and from the lungs separately and simultaneously, said catheter comprising a tubular 20 structure adapted to extend at least from the mouth of a patient to a point within the main bronchus of one lung, the distal end of said structure having a pre-formed and permanently-set arcuate configuration for facilitating entrance 25 into the said bronchus, an inflatable collar encircling the tubular structure at a position adjacent the distal end thereof and adapted to be positioned within the said bronchus, a second inflatable collar encircling the tubular structure at a position proximal to the first collar and which will be positioned within the trachea when the first collar is positioned within the bronchus of 30 one lung, said collars being adapted when inflated to seal the respective respiratory passages, 35 a single inflating duct extending longitudinally through a wall of said structure and communicating with both of said collars for conducting inflating fluid to the collars, the walls of said tubular structure having one opening distal to both 40 collars and a second opening between the two collars, a septum dividing the lumen of said tubular structure into two separate longitudinal conduits communicating respectively with the aforesaid two openings, said conduits and said inflating 45 duct diverging at the proximal end of the catheter and terminating in three separate tubular extensions adapted to be connected with appropriate fluid conductors, said catheter having an essentially integral unitary structure embodying 50 rubber as the principal constituent and being flexible throughout. 55
